FIREPLACE STOVE

Randolph T. Hanger, Seattle, and Joseph L. Phillips, Bellevue, Wash., assignors to International Dynamics, Inc., Seattle, Wash., a corporation of Washington

Filed Mar. 1, 1961, Ser. No. 64,112

Term of patent 14 years

(Cl. D81—7)

FIG. 1

FIG. 2

FIG. 3

FIGURE 1 is a front elevational view of a fireplace stove embodying our new design;

FIGURE 2 is a side elevation thereof; and

FIGURE 3 is a plan view thereof.

Our design for a fireplace stove is characterized by the specifically contoured hood portion in association with the base portion, all as shown.

We claim:

The ornamental design for a fireplace stove, as shown and described.
